UNITED STATES PATENT OFFICE.

ALEXANDER KNAPPENBERGER, OF SIEGFRIED, PENNSYLVANIA.

DUST SEPARATING AND COLLECTING APPARATUS.

No. 878,640.

Specification of Letters Patent.

Patented Feb. 11, 1908.

Application filed June 12, 1907. Serial No. 378,499.

To all whom it may concern:

Be it known that I, ALEXANDER KNAPPENBERGER, a citizen of the United States of America, residing at Siegfried, county of Northampton, in the State of Pennsylvania, one of the United States of America, have invented certain new and useful Improvements in Dust Separating and Collecting Apparatus; and I do hereby declare that the following is a full, clear, and exact description of the invention, such as will enable others skilled in the art to which it appertains to make and use the same.

My invention relates to dust collectors for mills and similar plants where it is desired to convey the heated air from the mill and to separate and collect the dust and other solid matter in the air.

The object of my invention is to provide a simple construction, which is effective in its operation and which may be adjusted to suit varying drafts and conditions of the air, and which may be easily applied to ordinary forms of stacks.

My invention consists of the construction, combination and arrangement of parts, as herein illustrated, described and claimed.

In the accompanying drawings, forming part of this application, I have illustrated one form of embodiment of my invention, in which drawings similar reference characters designate corresponding parts, and in which: Figure 1 is a central vertical section, partly in elevation; Fig. 2 is a horizontal section taken approximately on line 2—2 of Fig. 1, looking in the direction indicated by the arrow; and, Fig. 3 is a horizontal section taken approximately on line 3—3 of Fig. 1, looking in the direction indicated by the arrow.

Referring to the drawings, 1 designates a stack, on the upper end of which is disposed a casing 2, the lower wall of which is inclined towards its center.

Secured to the inner wall of the casing 2, is a plurality of brackets 3, adapted to receive angle irons 4, to which angle irons is secured the inwardly projecting flange 5 of a bell 6, which bell is disposed entirely within the casing 2, so as to leave a space 7 between its lower edge and the wall of the casing. This space is left so as to permit a draft upward through the casing, and the wall of the bell 6 is inclined downward and outward, so that any solid material which passes above the bell will fall thereon and be directed down-

ward and outward against the wall of the casing.

Slidably disposed on the upper end of the stack 1, below the bell 6, is a sleeve 8, on which is mounted rollers 9, adapted to receive flexible members 10, which flexible members support the sleeve 8. One end of the flexible member is secured to cleats 11 on the inner wall of the casing 2, and the opposite ends of the flexible members are disposed through openings 12 in the wall of the casing 2, and are provided with handles 13. Brackets 14 are secured on the outer wall of the casing 2 adjacent the openings 12, and have disposed thereon rollers 15, adapted to receive the flexible members 10, so that they may be easily moved. By pulling on the handles 13, the flexible members will be tightened to raise the sleeve 8, and thereby vary the distance between the upper end of the stack and the lower face of the bell 6, so that the draft through the stack and the casing 2 is varied to suit the conditions required. Solid matter in the air passing through the stack 1 will strike the under surface of the bell 6, and will be deflected downward thereby, and will fall to the bottom of the casing 2.

For the purpose of conducting the matter from the casing 2, tubes 16 are connected to the lower end thereof, and in turn are joined to a discharge pipe 17, the lower end of which has a pivoted closure 18, which prevents a back draft through the pipes 16.

Projecting within the casing 2 from its upper end, is an air exhaust pipe 19, which is surmounted by a hood 20 of common construction. Slidably disposed on the lower end of the pipe 19, within the casing 2, is a sleeve 21, provided with a lower outwardly extended flange 22, so that the sleeve 21 and its flange forms a bell disposed within the casing over the bell 6.

Mounted on the outside of the sleeve 21 are rollers 23, under which are disposed flexible members 24, having one of their ends secured to cleats 25 on the inner surface of the wall of the casing 2, and having their opposite ends carried through openings 26 in said wall. The outer ends of the flexible members 24 are provided with handles 27, and are disposed over rollers 28, carried on brackets 29 on the outer wall of the casing 2, so that the flexible members 24 may be easily moved.

By pulling on the handles 27, the sleeve 21

will be elevated so as to increase the distance between the lower surface of the flange 22 and the upper surface of the bell 6, so that the draft through the exit pipe 19 may be 5 varied to suit different conditions.

For the purpose of providing a structure which is easily removable, the casing 2 is preferably made in two sections, which may be easily joined together by means of angle 10 iron members 30, which angle irons may be riveted to the sections of the casing 2 and may be riveted together.

Having thus fully described my invention, what I claim as new, and desire to secure by 15 Letters Patent, is:—

1. A collector and separator comprising the combination of a stack, a casing on the stack brackets secured to the inner wall of the casing, a flanged bell secured on the 20 brackets, means for varying the space between the stack and the bell, an exit pipe projecting into the casing from its upper end, means for varying the space between the exit pipe and the bell, and means for conducting separated matter from the casing.

2. A collector and separator comprising the combination of a stack, a casing on the stack, a sleeve movably disposed on the stack within the casing, means for raising 30 the sleeve, a bell fixed above the sleeve, an exit pipe projecting into the casing above the bell, and means for varying the space between the exit pipe and the bell.

3. A collector and separator comprising the combination of a stack, a casing on the stack, a sleeve movably disposed on the stack within the casing, rollers on the sleeve, flexible members having one of their ends fixed and their opposite ends disposed 40 through the wall of the casing so that intermediate of their ends the flexible members pass under the rollers, a bell fixed above the sleeve within the casing, an exit pipe projecting into the upper end of the casing, and 45 means for varying the space between the exit pipe and the bell.

4. A collector and separator comprising the combination of a stack, a casing on the stack, a sleeve movably disposed on the 50 stack within the casing, rollers on the sleeve, flexible members disposed under the rollers and having one of their ends disposed

through openings provided in the wall of the casing, cleats secured on the inner wall of the casing, to which cleats are secured one 55 of the ends of the flexible members, brackets secured on the outer wall of the casing, rollers on the brackets over which the outer ends of the flexible members are disposed, a bell fixed within the casing above the sleeve, an exit pipe 60 extending within the upper end of the casing, and means for varying the space between the lower end of the exit pipe and the bell.

5. A collector and separator comprising the combination of a stack, a casing on the 65 stack, a bell fixed above the stack within the casing, means for varying the space between the bell and the stack, an exit pipe arranged on the casing above the bell, a sleeve slidably disposed on the lower end of the exit pipe 70 and provided with a downwardly inclined flange, and means for moving the sleeve on the exit pipe.

6. A collector and separator comprising the combination of a stack, a casing on the 75 stack, a bell fixed above the stack within the casing, means for varying the space between the bell and the stack, an exit pipe arranged on the casing above the bell, a sleeve slidably disposed on the lower end of the exit pipe 80 and provided with a downwardly inclined flange, rollers on the sleeve, flexible members having their ends fixed within the casing disposed under the rollers and projecting from the casing, and friction reducing members disposed under the flexible members 85 outside of the casing.

7. A collector and separator comprising the combination of a stack, a casing formed of two parts and disposed on the stack, angle 90 iron members connecting the two parts of the casing, a bell in the casing above the stack, means for varying the distance between the stack and the bell, an exit pipe projecting into the top of the casing, and 95 means for varying the distance between the exit pipe and the bell.

In witness whereof I have hereunto set my hand in the presence of two witnesses.

ALEXANDER KNAPPENBERGER
